LONGITUDINAL SPACER

Filed Oct. 26, 1923

Fig. 1.

Patented Feb. 10, 1925.

UNITED STATES PATENT OFFICE.

STEPHEN J. WOHLLEB, OF WEST NEW YORK, NEW JERSEY.

LONGITUDINAL SPACER.

Application filed October 26, 1923. Serial No. 671,045.

To all whom it may concern:

Be it known that I, STEPHEN J. WOHLLEB, a citizen of the United States, and a resident of West New York, county of Hudson, and State of New Jersey, have invented certain new and useful Improvements in Longitudinal Spacers, of which the following is a specification.

This invention relates to improvements in longitudinal spacers.

The object of this invention is to produce a column spacer which will effectively perform its function of spacing columns of type matter and, at the same time, will, by a longitudinal relative movement of the parts, compensate for the interstitial spaces between the lines of type when the same are closed up by the pressure of the quoins.

Another object of my invention is to provide a column spacer preferably of twelve point thickness formed of two interconnected spacing members, each preferably of a thickness of six points and having relative longitudinal movement to elongate the spacer and to permit a relative longitudinal contracting movement for the purpose of compensating for the slight interstitial spaces between the lines of type when the same are contracted or forced together by the pressure of the quoins, my said spacer, however, at the same time maintaining the proper spacing thickness throughout its length in any extended or contracted position.

Another object of my invention is to provide a column spacer of twelve point thickness composed of two abutting members, each of which will have at one end a cut-out portion intermediate its upper and lower edges, and at the opposite end a laterally-projecting block connected to the abutting face and also located intermediate the upper and lower edges to fit within the cut-out portion of the abutting member, said block having the thickness of the opposite member and its end flush with the end of said member, the said blocks at opposite ends being movable within the openings in the ends of the other member so as to form complements of the cut-out portions and to wholly fill the same when in contracted position.

Another object of the invention is to enable the secure attachment of the blocks in the openings in which they slide so as to retain the two members together and this is

preferably accomplished by providing the opposite side edges of the block with inclines so that the block is dove-tailed in cross-section and the openings have opposite walls which are similarly inclined to provide a dove-tailed seat for the said block.

With these and other objects in view, the invention comprises the combination of members and arrangement of parts so combined as to co-act and cooperate with each other in the performance of the functions and the accomplishment of the results herein contemplated, and comprises in one of its adaptations the species of preferred form illustrated in the accompanying drawings, in which:—

Fig. 1 is a portion of a chase in which I have shown two columns locked up and separated by my improved compensating column spacer;

Fig. 2 is a perspective view of the two members of my compensating column spacer separated from each other;

Fig. 3 is a plan view of the two members coupled together and in extended position;

Fig. 4 is a similar plan of my said column spacer in fully contracted position;

Fig. 5 is a side elevation in extended position; and

Fig. 6 is an end view of my said column spacer.

Referring now to these drawings which illustrate a preferred embodiment of my invention, 1 indicates a portion of one end of a chase or frame in which I have shown columns 2 and 3 comprising a series of lines of type locked up by quoins 4 located between reglets 5, the column forms 2 and 3 being surrounded by blocks 6 or other suitable furniture in the usual way. The columns 2 and 3 are, as shown, separated partially by a reglet 7 and my column separator 8 arranged, as shown, at one end of said reglet.

My improved column separator comprises, as shown, two identical members 9 each comprising a body portion 9^a preferably of a six point thickness and of a height less than type high. Connected at one end of the body portion 9^a and intermediate the upper and lower edges thereof is a block 10 which is arranged with its end flush with the end 9^b of the body portion 9^a and is less than the height of the member so as to leave spaces 9^c at opposite sides thereof. The block 10 is preferably provided with

opposite inclined edges 10^a and the block will therefore be dove-tailed in end elevation or cross-section. The opposite end of the body portion 9^a is provided with an opening 11 of a size adapted to fit snugly over the block 10 on the opposite member and form a seat therefor. This opening 11 is provided with inclined side walls 11^a which form ways on which the inclined edges 10^a of the block 10 are adapted to slide.

It will be apparent that the open or bifurcated end of one member may be slid over the block of the other member and vice versa, so that the faces 9^d of the members will abut one against the other and slide on each other, and the members will have a longitudinal sliding movement along such abutting faces 9^d.

It will be seen that when the members are so inter-connected with the seat of one member engaging the block of the other member that a sliding of the members longitudinally will cause the ends having the blocks to be moved longitudinally beyond the ends having the openings and that when so elongated the two body portions 9^a and the blocks 10 will preserve the thickness of the spacer when elongated within the limits of the length of the block and opening, and that pressure on either of the opposite ends will cause a collapsing or contracting of the length of the spacer so as to fit the space exactly and to compensate for the compression of the printed matter when the quoins 35 are applied to bind the same together, and to close up any interstitial spaces between the lines of type themselves or between spacing leads and such lines of type.

It will also be obvious that my spacer may be used under other conditions than those shown, as for example, at the margins of columns or pages adjacent to rulers and that when so utilized the transverse rulers may be brought more neatly into contact with the longitudinal rulers because of the compensating nature of my spacer which in such cases may be placed adjacent to and parallel with said longitudinal rulers.

Having described my invention, I claim:—

50 1. A longitudinal spacer for type matter embodying a pair of similar members, each having a body portion slidable in relation

to the other member of the pair and having at opposite ends and intermediate the upper and lower edges thereof a laterally projecting block on the body portion of one member and a block seat in the body portion of the opposite member, the said blocks being of substantially similar thickness to the said body portions of the members and being slidable within the block seat to permit an elongation of the body portions of the members while maintaining the double thickness thereof intermediate the upper and lower edges thereof.

2. A longitudinal spacer for type matter embodying two similar members less than type high and having at opposite ends and intermediate the upper and lower edges thereof a laterally projecting block on one member and a block seat in the opposite member, the said blocks being of substantially similar thickness to the said members and being slidable within the block seat to permit an elongation of the member while maintaining the double thickness thereof intermediate the upper and lower edges thereof, each block having inwardly inclined side edges to cause the block to be dove-tailed in cross-section and the seats in 80 the opposite members being provided with walls having similarly inclined edges so as to engage and snugly slide over the said block.

3. A double spacing block embodying two members each comprising a body portion less than type high and of a thickness substantially equal to six points, a block connected to one face of said body portion intermediate the upper and lower edges thereof, a block seat in the adjacent end of the abutting member of substantially similar conformation and size as said block so as to fit over the same and permit a sliding engagement between the two members and a 95 similar reversed block and seat at the opposite ends of said spacer.

In witness whereof, I have signed my name to the foregoing specification in the presence of two subscribing witnesses.

STEPHEN J. WOHLLEB.
